CARD PUNCHING STYLUS

Ira G. Laws and Edward J. Crossland, Tulsa, Okla., assignors to Seismograph Service Corporation, Tulsa, Okla.

Filed Dec. 2, 1968, Ser. No. 14,753

Term of patent 14 years

Int. Cl. D19—99

U.S. Cl. D74—1

FIG. 1

FIG. 2

FIG. 3

FIG. 1 is a top view of a card punching stylus according to the present invention;

FIG. 2 is an elevational view of the card punching stylus; and

FIG. 3 is a bottom view of the card punching stylus.

The stylus in cross section is circular, and the rear, left side and right side views are identical with the front elevational view.

We claim:

The ornamental design for a card punching stylus, substantially as shown and described.
